AMMUNITION FEEDING DEVICE

Clarence E. Gaskill, Mason, and Harvey J. Hackman, Kings Mills, Ohio, assignors to Remington Arms Company, Inc., a corporation of Delaware

Application June 29, 1940, Serial No. 343,142

18 Claims. (Cl. 193—43)

The present invention relates to an indexing device for shot shells or the like, and particularly such device for receiving shot shells as they emerge from a loading apparatus and arranging them in side-by-side heads-tails sequence preparatory to the mechanical packing of the shells in boxes. It is an object of the invention to provide a device of this character into which the shot shells may flow from the loader without regard to the speed or synchronization of the rate of flow, and in which positive indexing means for reversing the position of the alternate shells is operated through direct contact of the individual shells, to the end that such device is always in the correct position to give the proper sequence, whether the shot shells flow from the loader intermittently or en masse. It is a further object to provide indexing means, which is in the form of a gravity-operated diverting lever, arranged to have relatively frictionless oscillatory movement into its two operative positions through the weight and movement of the individual shot shells dropping into cooperative engagement therewith.

A further object is to provide a mechanism whereby the shot shells may be released in pairs in the event that there is any congestion on the track leading to the packaging apparatus, and which will continue to release the shot shells in pairs as long as the congestion continues, without the necessity for stopping the flow of the shot shells from the loader. As a consequence the proper heads-tails sequence of the shells, with the brass ends alternately arranged in reversed relation, will be maintained.

Another object is to provide an indexing device which is capable of adjustment to accommodate shot shells of varying diameters and lengths, without any alteration or substitution in the parts, so that one standardized type of machine may be economically manufactured in quantity and through proper adjustment the individual machines may be adapted for use in connection with loaders producing different sizes of shot shells.

With the above and other objects in view, an embodiment of the invention is shown in the accompanying drawings, and this embodiment will be hereinafter more fully described with reference thereto, and the invention will be finally pointed out in the claims.

In the drawings:

Fig. 1 is a front elevation of an indexing device, according to the illustrated exemplary embodiment of the invention, the course of the shot

shells through the indexing part of the device being shown in dot-and-dash lines, and the open position of the door normally closing the front of the shell diverting passages being shown in 5 dot-and-dash lines.

Fig. 2 is a fragmentary rear elevation of the upper section of the device.

Fig. 3 is a side elevation, the upper portion of the feeding hopper being broken away.

10 Fig. 4 is a top plan view, the lower portion of the feeding hopper being shown in horizontal section along the line 4—4 of Fig. 3.

Fig. 5 is a horizontal sectional view taken along the staggered line 5—5 of Fig. 3.

15 Fig. 6 is a vertical sectional view, taken along the staggered line 6—6 of Fig. 1, and showing several of the shot shells in their positions during normal passage through the machine.

Fig. 7 is a vertical transverse sectional view 20 taken along the line 7—7 of Fig. 6, the several shot shells as shown in Fig. 6 being removed however.

Fig. 8 is a fragmentary vertical sectional view 25 showing the operation of the releasing mechanism during congestion of the passage of the shot shells on the track to the packaging apparatus.

Similar reference characters indicate corresponding parts throughout the several figures of the drawings.

30 Referring to the drawings, the supporting frame of the machine consists of a pair of vertical standards 10—10, provided at their lower ends with right angularly bent bases 11—11 which may be suitably anchored to the floor, and 35 having supported for vertical adjustment upon their upper ends a rectangular vertically disposed plate 13, secured to the standards by means of bolts 14 engaged through slots 15 in the standards and which permit of limited vertical adjustment 40 of the plate relative to the standards.

At the upper end of the plate 13 there is secured upon its rearward face an angular bracket member 16, the vertical portion of which is secured to the plate for limited vertical adjustment 45 by means of bolts 17 screwed into the plate 13 and engaged through slots 18 in the bracket, and the horizontal portion of which projects forwardly in spaced relation above the upper edge of the plate 13, where it is provided with a vertically disposed passage 19. Upon this horizontal portion of the bracket 16 there is mounted the shot shell feeding hopper 20 having at its lower end a pair of outwardly bent foot portions 21—21 secured to the bracket 16 by means of bolts 50 22—22. This hopper is contracted at its lower

portion to provide a passage for the individual vertical gravity feeding of the shot shells A downwardly with their brass flanged ends A¹ disposed downwardly, this being the arrangement in which they flow from the loader. The upper enlarged portion of the hopper is curved into line with the downwardly inclined guideway feeding the shot shells from the loader, this guideway being formed by rods 23 secured at their lower ends in an apertured collar 24 secured to the mouth of the hopper.

Upon the forward face of the plate 13 there is provided in centralized relation along the vertical center line of the plate a substantially circular block member 25, secured to the plate by screws 26-26, and in the front face of which there is provided a vertical slot 27 in which a bearing bracket bar 28 is secured by means of screws 29-29, the upper end of this bracket bar projecting above the upper end of the block and being provided with a bearing 30 for the forward end of the shot shell diverting index lever member 31. This index lever member consists of a vertically disposed upwardly projecting central arm 32 arranged to be swung to and fro between its two operative positions as shown by the full and dot-and-dash lines in Fig. 1, to constitute the respective entrances to the left and right passages through the shell reversing portion of the machine. The side walls of the arm 32 are curved downwardly and outwardly in diverging relation and merge into the upper curved surfaces of a pair of outwardly curved side arms 33-33. The hub portion of the index lever member 31 is secured to a horizontal shaft 34 by means of a set screw 35, the forward end of this shaft being engaged for free turning movement in the bearing 30 of the bracket bar 28, and its rearward end extending through a bearing 36 in the plate 13, where it is provided at the rearward side of the plate 13 with a segmental movement limiting and counterbalance member 37, the hub of which is secured to the shaft by a cross pin 38. The oscillatory movement of this counterbalance member is limited by adjustable stop screws 39-39 mounted in a bracket bar 40 secured to the rearward side of the plate 13 by means of screws 41-41. Through vertical adjustment of the stop screws 39-39 the extent of the oscillatory movement of the index lever member 31 may be regulated, as desired, this adjustment being mainly for the purpose of accommodating the machine to various diameters of shot shells, increase or decrease in the extent of the swing of the upper end of the arm 32 increasing or decreasing the width of the entrances to the right and left shot shell diverting passages. The counterbalance member 37 constitutes an over-center weight which retains the index lever member 31 in either of its operative positions by gravity, the lever member being moved to an over-center position through the weight and movement of the shot shells, as will presently more fully appear.

At each side of the index lever member 31, and the block 25, there is provided a wall member 42, the upper portion of which is inclined downwardly and outwardly in outwardly spaced relation to the lever member 31 and the lower portion of which is curved downwardly and inwardly in outwardly spaced relation to the block member 25, the upper vertical end portions 43-43 of these wall members being respectively secured as by welding, to angular brackets 44-44 mounted for horizontal adjustment upon the plate 13 by

means of bolts 45-45 engaging slots 46-46 in the respective brackets, and the lower vertical end portions 47 being similarly secured to angular brackets 48-48 mounted for horizontal adjustment upon the plate 13 by means of bolts 49-49 engaging slots 50-50 in the respective brackets. The two wall members 42 constitute the outer walls of a shot shell indexing chamber having right and left shot shell diverting passages at the respective sides of the index lever member 31 and block 25 through which the shot shells flow downwardly from the hopper and pass alternately through the right and left passages, as will presently be more fully explained.

The passages through the indexing chamber are normally closed at the front by means of an apertured frame like door member 51, substantially corresponding to the general shape of the passages, this door member being hingedly mounted at one vertical edge by means of a hinge connection 52 supported upon an angular hinge bracket 53 secured to the rearward side of the plate 13 by means of screws 54. At the other vertical edge the door member is provided with a catch handle 55 releasably engaged by a spring catch member 56 secured to one side of the plate member 13 by means of screws 57. This door member is shown in dot-and-dash lines in Fig. 1 in its open position to permit free access to the passages.

As the shot shells flow downwardly from the hopper they alternately pass through the diverging right and left passages as indicated by the dot-and-dash lines. As shown in the illustration one shot shell is moving downwardly through the right hand passage having first engaged the index lever member 31 with the latter in the position shown in dot-and-dash lines, causing this lever to swing in clockwise direction to the full line position through the weight and movement of the shot shell. During this movement the lower flanged brass capped end A¹ of the shot shell engages the upper end of the arm 32 and then moves downwardly along the concavely curved surface to the lower end of the arm 33, the upper portion of the shot shell following in this movement. As the shot shell reaches the point where its weight overbalances the over-center weight of the index lever member the latter swings from the dot-and-dash line position to the full line position, the shot shell continuing its movement downwardly around the block member 25 and being guided by the side wall 42, so that its brass end is projected across the lower end of the chamber into engagement with the opposed shoulder portion 47 of the left hand side wall 42, and as indicated by the arrows and the dot-and-dash lines. Upon striking this point the shot shell swings downwardly into horizontal position and drops through the exit end of the chamber, this swinging movement being substantially about the point of contact of the brass end of the shot shell with the shoulder portion 47 as a fulcrum, so that this shot shell has its flanged brass end at the left. The following shot shell flowing downwardly from the hopper moves downwardly through the left hand passage in the same manner, the index lever member 31 in its position as indicated in full lines constituting an entrance guide to this left hand passage. The brass capped end of this shot shell strikes the opposed right hand vertical shoulder portion 47, as indicated by the arrow, the shot shell swinging downwardly into horizontal position to drop through the exit end of the chamber with its

flanged brass end at the right. This sequence continues as long as the shot shells flow from the loader.

Directly below and extending forwardly from the exit end of the indexing chamber there is provided the part of the device which guides the alternately reversed shot shells to the track leading to the packaging apparatus, and in which there is provided the over-flow release means which in the event of an impedance in the normal flow of the shot shells to the packaging apparatus releases them in pairs so that upon resumption of the normal flow, the heads-tails sequence of the shot shells is not interrupted.

This part of the device consists of a fixed block member 58, directly below the exit end of the indexing chamber, secured to the forward face of the plate 13 by means of bolts 59-59, the upper face of this block member being inclined downwardly and forwardly and rounded at its forward edge. The lower face of the block member 58 is also inclined forwardly and downwardly but at a slightly smaller degree than the inclination of the upper face, and there is mounted upon the plate 13 below the block member 58 and in engagement with its lower face a pair of forwardly projecting block members 60-60 which are secured to the plate 13 for horizontal adjustment by means of bolts 61-61, rewed into the respective block members 60-60 and engaged through horizontal slots 62-62 in the plate 13. The block members 60-60, as seen clearly in Fig. 7, extend outwardly beyond the side edges of the block member 58 and are respectively provided with downwardly offset recessed passages 63-63 outwardly of the block member 58, these passages being for the purpose of providing a free-way for the flanged brass ends A¹ of the shot shells A, the intermediate cylindrical portions of the shot shells rolling downwardly upon the inclined upper surface of the block members 60-60 between the recessed passages 63.

Upon each block member 60 there is secured a side wall member 64 having at its inner face a bearing plate 65 for engagement by the flanged brass ends of the shot shells, the side wall member and the plate member 65 being rigidly secured to the block member by a pair of bolts 66-66. The side wall members 64 are of irregular shape and extend above the block member 60 at their rearward portions, their forward portions being of stepped formation to provide bearing supports projecting forwardly of the forward ends of the block members 60. The bearing plates 65 are also of irregular shape, their upper edges extending in parallel spaced relation along the recessed passages 63 and then extending downwardly and forwardly at the forward end of the block members 60 to follow the passage of the shot shells, as will presently more fully appear.

Directly above the upper inclined surface of the blocks 60 there are provided a pair of spaced freely swinging gate members 67 and 68 mounted upon horizontal shafts 69 and 70 respectively, these shafts being journaled for free rotation in the side wall members 64 and being provided respectively at one end with heads 71 and 72 and at the other end with adjustable collars 73 and 74. These gate members, which normally hang vertically, are engaged by the shot shells as they roll from the block member 58 along the block members 60, and through engagement with the cylindrical surfaces thereof tend to maintain them in parallel relation and to retard their

velocity, so that as they roll down the inclined surfaces of the blocks 60 they are maintained in parallel and separated relation, each gate as it clears one shell immediately dropping behind it so that it is interposed between this shell and the successive shell.

In forwardly spaced relation to the forward ends of the block members 60 there are provided a pair of vertically disposed abutment plate members 75-75 provided respectively with angular attaching bracket portions 76-76 secured for horizontal adjustment upon the side wall members 64 by means of screws 77-77 engaging slots 78-78 in the respective bracket portions, these abutment members constituting a forward wall for the vertical passage through which the shot shells drop downwardly as they leave the forward edge of the block members 60. Forming the bottom of this vertical passage is a trap-door platform member 79 provided centrally at its rearward edge with an upwardly projecting bearing ear 80 engaged upon a transverse rock shaft 81 rotatably mounted in bearing passages 82 formed in the block members 60, a head 83 being provided at one end disposed at the outer side of one of the side wall members 64 and the other end being provided with an adjustable collar 84 disposed at the outer side of the other side wall member 64. The ear 80 is adjustably secured upon the shaft 81 by means of a set screw 85, and the collar 84 is adjustably secured by means of a set screw 86, so that upon relative lateral adjustment of the side wall bearing members, to accommodate the machine to different lengths or sizes of shot shells, the platform may be properly adjusted into centralized position between them.

Upon the outer end of the rock shaft 81 there is mounted the hub 87 of a screw threaded counter-weight supporting shaft 88 projecting from the shaft in the opposite direction from the trap-door platform member 79, the hub 87 being secured to the shaft by means of a set screw 89. A counter-weight 90 is adjustably engaged upon the shaft 88, its adjusted position being fixed by means of lock nuts 91 and 92. This counter-weight normally supports the trap door platform member 79 in its normal shell supporting position, as shown in Fig. 6, which position is determined by a stop screw 93 adjustably mounted in an angular bracket 94 secured upon the standard 10 by means of a bolt 95, the adjusted position of the screw 93 being fixed by means of a lock nut 96.

The forward end of the trap door platform member 79 is normally disposed slightly above and adjacent the end of an inclined trackway consisting of a pair of angular supporting members 97-97 which are respectively secured to the inner sides of the forward end portions of the side wall members 64 by means of angular brackets 98 secured by bolts 99. Upon the upper surfaces of the track members 97 there are secured strip members 100-100 which are spaced from the side walls of the track members to provide recessed passageways in which the flanged brass ends A¹ of the shot shells move, the strip members supporting the cylindrical intermediate portions of the shells.

Forwardly of the abutment wall member 75 there is provided a freely swinging gate member 101 having its shaft 102 journaled for free rotary movement in the side wall members 64, the shaft being provided at one end with a head 103 and at its other end with an adjustable col-

lar 104. This gate member controls the passage between the trap door platform member 79 and the inclined trackway to dispose the shot shells in parallel relation as they move from the platform member to the trackway and to retard their velocity.

An inclined chute consisting of a pair of angle iron members 105—105 is supported from the side wall members 64 by means of angular bracket members 106—106 which are secured by the same bolts 99 which secures the bracket members 98. The angle iron members 105 are respectively provided with strip members 107—107 spaced from the side walls so as to provide recessed passages for the flanged brass ends of the shot shells. This chute member has its upper end disposed beneath the trap door platform member 79 and is adapted to convey pairs of shells which are released by the trap door platform member, as will presently more fully appear, to a suitable receptacle.

During the normal operation of the machine the shot shells roll along the inclined block members 58 and 60 in alternately reversed or heads-tails sequence and in separated relation to each other, dropping from the end of the block member 60 upon the platform 79 and thence rolling onto the inclined track 97 which conveys them to the packaging apparatus. The counterbalance 90 for the trap-door platform member 79 is so adjusted that the platform will support the weight of one shot shell but will not support the weight of two shot shells. Consequently when there is an impedance in the flow of the shot shells along the trackway for any cause, and which causes them to accumulate up to the gate 101, as shown in Fig. 8, the next shot shell falling upon the platform 79 is not permitted to roll clear of it on to the track before another shot shell drops off the end of the block members 60, and thus the combined weight of two shot shells is imposed upon the platform member overbalancing the counterbalance 90 and causing the platform member to open downwardly to release the two shot shells. The trap door platform immediately closes as the released pair of shot shells roll clear, and as long as the congestion continues this operation of releasing pairs of shot shells will continue until the flow of the shells on the track resumes. It will therefore be seen that by the releasing of pairs of shot shells the heads-tails sequence of the shells upon the trackway will be automatically maintained.

In order to adjust the device to accommodate different sizes of shot shells it is only necessary to loosen the bolts 45—45 and 49—49 securing the side wall members 42 to permit these side wall members to be adjusted inwardly or outwardly to thereby decrease or increase the width of the passages through the indexing chamber, the adjusted position being fixed by tightening the bolts 45 and 49. The part of the device for guiding the shot shells to the packaging apparatus, and including the automatic releasing means, is correspondingly adjusted by loosening the bolts 61 which secure the block members 60 to the plate 13, and adjusting these block members inwardly or outwardly to the desired position, these block members have respectively supported upon them the side wall members 64 which in turn support the trackway 97 and chute 105. During this latter adjustment the set screws securing the collars 73, 74, 84 and 104, as well as the set screw securing the supporting ear 80 of the trap door platform member 79, are loosened

and upon completion of the adjustment are tightened to secure the collars and ear in their adjusted positions. The swing of the index lever member 31 is also adjusted to decrease or increase the width of the entrances to the right and left passages through the indexing chamber, as desired. The width of the vertical passage above the trap-door platform member 79 may be adjusted to accommodate different diameter shot shells by loosening the screws 11—11 and horizontally adjusting the wall members 75—75 forwardly or backwardly, as desired.

The form of the invention illustrated in the drawing and described herein is typical and illustrative only, and it is evident that the invention is capable of embodiments in other forms, all falling within the scope of the appended claims, which are to be broadly construed.

What is claimed is:

1. An indexing device for disposing articles such as shot shells in side-by-side heads-tails sequence, comprising a feeding hopper having a delivery end to feed said articles singly in end-to-end arrangement, an index chamber having side walls and an entrance end arranged to receive said articles from said hopper and an exit end adapted to deliver said articles, said chamber having left and right passages diverging outwardly from said entrance end and converging inwardly toward said exit end to arrange the articles in side-by-side heads-tails sequence, positive automatic index means in said chamber for alternately diverting said articles into said left and right passages, and guide means arranged to receive said articles from said chamber in said side-by-side heads-tails sequence.

2. An indexing device for disposing articles such as shot shells in side-by-side heads-tails sequence, comprising a feeding hopper having a lower delivery end to feed said articles singly in end-to-end vertical arrangement, an index chamber having side walls and an upper entrance end arranged to receive said articles vertically from said hopper and a lower exit end adapted to deliver said articles in horizontal arrangement, said chamber having left and right passages diverging outwardly from said entrance end and converging inwardly toward said exit end to arrange the articles in side-by-side heads-tails sequence, positive automatic index means in said chamber for alternately diverting said articles into said left and right passages, and guide means arranged to receive said articles from said chamber in said horizontal side-by-side heads-tails sequence.

3. An indexing device for disposing articles such as shot shells in side-by-side heads-tails sequence, comprising a feeding hopper having a delivery end to feed said articles singly in end-to-end arrangement, an index chamber having side walls and an entrance end arranged to receive said articles from said hopper and an exit end adapted to deliver said articles, said chamber having left and right passages diverging outwardly from said entrance end and converging inwardly toward said exit end, index means in said chamber for alternately diverting said articles into said left and right passages, inclined track means arranged to receive said articles from said chamber in side-by-side heads-tails sequence, and a weight releasable article supporting means arranged between said chamber and said track means, adapted to receive and support said articles singly in their transition to said track means, and being releasable upon the

imposition thereon of weight in excess of a single article, whereby said articles are released in pairs during impedance of the flow of the articles on said track means.

4. In an indexing device for disposing articles such as shot shells in side-by-side heads-tails sequence, an index chamber having side walls, an upper entrance end adapted to receive said articles vertically and a single lower exit end adapted to deliver said articles horizontally, said chamber having left and right passages diverging downwardly from said entrance end and converging inwardly toward said exit end, and index means movably mounted in said chamber for to and fro movement respectively to the right and left of said entrance end to constitute an entrance guide respectively for said left and right passages.

5. In an indexing device for disposing articles such as shot shells in side-by-side heads-tails sequence, an index chamber having side walls, an upper entrance end adapted to receive said articles vertically and a lower exit end adapted to deliver said articles horizontally, said chamber having left and right passages diverging downwardly from said entrance end and converging inwardly toward said exit end, index means movably mounted in said chamber for to and fro movement respectively to the right and left of said entrance end to constitute an entrance guide respectively for said left and right passages, and adapted to be moved to and fro through the successive engagement of said articles therewith, and adjustable stop means arranged to limit the oscillatory movement of said index means, adapted through adjustment to vary the extent of movement of said entrance guide.

6. In an indexing device for disposing articles such as shot shells in side-by-side heads-tails sequence, an index chamber having side walls, an upper entrance end adapted to receive said articles vertically and a single lower exit end adapted to deliver said articles horizontally, said chamber having left and right passages diverging downwardly from said entrance end and converging inwardly toward said exit end, an oscillatory index lever member mounted in said chamber having a centrally disposed arm portion adapted to be oscillated respectively to the right and left of said entrance end to constitute an entrance guide respectively for said left and right passages, and having downwardly extending diverging side arm portions adapted to be engaged by the articles to impart oscillatory movement to said index lever member whereby said centrally disposed arm is alternately moved over center to the right and left through the successive engagement of said articles with said respective side arms.

7. In an indexing device for disposing articles such as shot shells in side-by-side heads-tails sequence, an index chamber having side walls, an upper entrance end adapted to receive said articles vertically and a lower exit end adapted to deliver said articles horizontally, said chamber having left and right passages diverging downwardly from said entrance end and converging inwardly toward said exit end, the side wall at each side of said exit end constituting an abutment opposed to the lower end of the passage respectively at the opposite side of said chamber, and index means movably mounted in said chamber for to and fro movement respectively to the right and left of said entrance end to constitute an entrance guide respectively for said left and

right passages, and adapted to be moved to and fro through the successive engagement of said articles therewith.

8. In an indexing device for disposing articles such as shot shells in side-by-side heads-tails sequence, an index chamber having side walls, an upper entrance end adapted to receive said articles vertically and a lower exit end adapted to deliver said articles horizontally, said chamber having left and right passages diverging downwardly from said entrance end and converging inwardly toward said exit end, the side wall at each side of said exit end constituting an abutment opposed to the lower end of the passage respectively at the opposite side of said chamber, and index means movably mounted in said chamber for to and fro movement respectively to the right and left of said entrance end to constitute an entrance guide respectively for said left and right passages, and adapted to be moved to and fro through the successive engagement of said articles therewith, the article flow lines from said respective passages to said opposed abutments being at acute angles to said horizontal exit end and intersecting each other at a point centrally above said exit end.

9. In an indexing device for disposing articles such as shot shells in side-by-side heads-tails sequence, an index chamber comprising a vertical support member, a pair of laterally spaced side wall members adjustably mounted on said support member for lateral adjustment toward and away from each other, the upper spaced ends of said side wall members constituting an upper entrance end adapted to receive said articles vertically and their lower spaced ends constituting a lower exit end adapted to deliver said articles horizontally, said side wall members diverging downwardly from said entrance end and converging inwardly toward said exit end to provide left and right passages, an index means movably mounted in said chamber for to and fro movement respectively to the right and left of said entrance end to constitute an entrance guide respectively for said left and right passages.

10. In an indexing device for disposing articles such as shot shells in side-by-side heads-tails sequence, an index chamber having side walls and an upper entrance end shaped to receive said articles vertically, said chamber having left and right passages diverging from said entrance end and converging inwardly toward said exit end, index means movably mounted in said chamber for to and fro movement respectively to the right and left of said entrance end to constitute an entrance guide respectively for said left and right passages, and a movable closure member removably engaged with the forward side of said index chamber and constituting the front walls of said passages.

11. In an indexing device for disposing articles such as shot shells in side-by-side heads-tails sequence, an index chamber having side walls, an upper entrance end adapted to receive said articles vertically and a lower exit end adapted to deliver said articles horizontally, index means in said chamber adapted to alternately invert said articles whereby they are delivered in horizontal side-by-side heads-tails sequence, inclined guide means arranged below said chamber to receive said articles in horizontal side-by-side heads-tails sequence, inclined track means adapted to receive said articles from said inclined guide means, and a series of freely swinging vertically disposed gate members parallel to the width of said guide

means disposed in the path of said articles moving thereon to be swingingly moved by said articles to permit their passage, said gate means being spaced to receive a single article between them and whereby the articles are maintained in spaced parallel relation during their movement along said guide means and their velocity is retarded.

12. In an indexing device for disposing articles such as shot shells in side-by-side heads-tails sequence, an index chamber having side walls, an upper entrance end adapted to receive said articles vertically and a lower exit end adapted to deliver said articles horizontally, index means in said chamber adapted to alternately invert said articles whereby they are delivered in horizontal side-by-side heads-tails sequence, inclined guide means arranged below said chamber to receive said articles in horizontal side-by-side heads-tails sequence, downwardly extending passage means in communication at its upper end with the end of said guide means to receive said articles singly, inclined track means communicating with the lower end of said downwardly extending passage means arranged to receive said articles in side-by-side heads-tails sequence, and inclined weight releasable article supporting means constituting the bottom of said downwardly extending passage means and arranged contiguous to said inclined track means adapted to receive and support said articles singly in their transition to said track means, and being releasable upon the imposition thereon of weight in excess of a single article whereby said articles are released in pairs during impedance of the flow of the articles on said track means.

13. In an indexing device for disposing articles such as shot shells in side-by-side heads-tails sequence, an index chamber having side walls, an upper entrance end adapted to receive said articles vertically and a lower exit end adapted to deliver said articles horizontally, index means in said chamber adapted to alternately invert said articles whereby they are delivered in horizontal side-by-side heads-tails sequence, inclined guide means arranged below said chamber to receive said articles in horizontal side-by-side heads-tails sequence, downwardly extending passage means in communication at its upper end with the end of said guide means to receive said articles singly, inclined track means communicating with the lower end of said downwardly extending passage means arranged to receive said articles in side-by-side heads-tails sequence, and inclined weight releasable article supporting means constituting the bottom of said downwardly extending passage means and arranged contiguous to said inclined track means adapted to receive and support said articles singly in their transition to said track means, and being releasable upon the imposition thereon of weight in excess of a single article whereby said articles are released in pairs during impedance of the flow of the articles on said track means, said releasable article supporting means comprising a horizontal rock-shaft, a platform member secured to said rock-shaft extending in one direction, an adjustable counterweight member secured to said rock-shaft extending in the opposite direction, and adjustable stop means arranged to support said counterweight member in a predetermined position.

14. In an indexing device for disposing articles such as shot shells in side-by-side heads-tails sequence, an index chamber having side walls,

an upper entrance end adapted to receive said articles vertically and a lower exit end adapted to deliver said articles horizontally, index means in said chamber adapted to alternately invert said articles whereby they are delivered in horizontal side-by-side heads-tails sequence, inclined guide means arranged below said chamber to receive said articles in horizontal side-by-side heads-tails sequence, downwardly extending passage means in communication at its upper end with the end of said guide means to receive said articles singly, inclined track means communicating with the lower end of said downwardly extending passage means arranged to receive said articles in side-by-side heads-tails sequence, horizontally adjustable wall means opposed to the end of said guide means constituting the forward wall of said downwardly extending passage means and adapted through adjustment to vary the width of said passage means, and inclined weight releasable article supporting means constituting the bottom of said downwardly extending passage means and arranged contiguous to said inclined track means adapted to receive and support said articles singly in their transition to said track means, and being releasable upon the imposition thereon of weight in excess of a single article whereby said articles are released in pairs during impedance of the flow of the articles on said track means.

15. In an indexing device for disposing articles such as shot shells in side-by-side heads-tails sequence, an index chamber having side walls, an upper entrance end adapted to receive said articles vertically and a lower exit end adapted to deliver said articles horizontally, index means in said chamber adapted to alternately invert said articles whereby they are delivered in horizontal side-by-side heads-tails sequence, inclined guide means arranged below said chamber to receive said articles in horizontal side-by-side heads-tails sequence, downwardly extending passage means in communication at its upper end with the end of said guide means to receive said articles singly, inclined track means communicating with the lower end of said downwardly extending passage means arranged to receive said articles in side-by-side heads-tails sequence, inclined weight releasable article supporting means constituting the bottom of said downwardly extending passage means and arranged contiguous to said inclined track means adapted to receive and support said articles singly in their transition to said track means, and being releasable upon the imposition thereon of weight in excess of a single article whereby said articles are released in pairs during impedance of the flow of the articles on said track means, and a freely swinging vertically disposed gate member parallel to the width of said track means disposed in the path of said articles moving from said weight releasable supporting means to said track means to be swingingly moved by said articles to permit their passage.

16. In an indexing device for disposing articles such as shot shells in side-by-side heads-tails sequence, an index chamber having side walls, an upper entrance end adapted to receive said articles vertically, and a lower exit end adapted to deliver said articles horizontally, a block member having a downwardly and forwardly inclined upper surface disposed directly below said exit end to receive said articles in horizontal heads-tails sequence, downwardly inclined guide means be-

low and extending forwardly from said block member, and a freely swinging vertically disposed gate member parallel to the width of said block member and guide means disposed in the path of said articles moving from said block member to said guide means to be swingingly moved by said articles to permit their passage.

17. In an indexing device for disposing articles such as shot shells in side-by-side heads-tails sequence, a vertically disposed supporting member, index chamber means carried thereby having side walls, an upper entrance end adapted to receive said articles vertically, and a lower exit end adapted to deliver said articles horizontally and in side-by-side heads-tails sequence, positive automatic index means in said chamber adapted to alternately divert said articles whereby they are delivered in horizontal side-by-side heads-tails sequence, inclined guide means arranged below said chamber to receive said articles in horizontal side-by-side heads-tails sequence comprising a pair of members, and means mounting said members on said support for horizontal adjustment movement toward and away from each other to vary the width of said guide means.

18. In an indexing device for disposing articles such as shot shells in side-by-side heads-tails sequence, a vertically disposed supporting member, index chamber means carried thereby having side walls, an upper entrance end adapted to receive said articles vertically, and a lower exit end adapted to deliver said articles horizontally, in-

dex means in said chamber adapted to alternately divert said articles whereby they are delivered in horizontal side-by-side heads-tails sequence, inclined guide means arranged below said chamber to receive said articles in horizontal side-by-side heads-tails sequence comprising a pair of members, means mounting said members on said support for horizontal adjustment movement toward and away from each other to vary the width of said guide means, a pair of side wall members respectively secured to the outer sides of said pair of guide members extending forwardly from said guide members to provide downwardly extending passage means at the forward ends of said guide members, inclined track means comprising a pair of track members respectively secured to the forward ends of said side wall members in forwardly spaced and downwardly offset relation to the forward ends of said guide members, and weight releasable article supporting means constituting the bottom of said downwardly extending passage means, arranged contiguous to said track means adapted to receive and support said articles singly in their transition to said track means, and being releasable upon the imposition thereon of weight in excess of a single article whereby said articles are released in pairs during impedance of the flow of said articles on said track means.
